UNITED STATES PATENT OFFICE.

BENJAMIN G. RAND, OF NORTH TONAWANDA, NEW YORK.

ATTACHMENT FOR ADDRESSING MACHINES AND THE LIKE.

Application filed October 24, 1924. Serial No. 745,674.

This invention relates generally to a printing apparatus, but more particularly to an attachment for addressing machines and the like.

5 Its principal object is to provide a novel attachment of this character which permits of transposing or reproducing the usual grouped or vertical arrangement of the address on the printing plate in a substantially horizontal line on the printed card or other receiving surface. This is desirable, for example, in so-called visible card indexes composed of overlapping hinged leaves, each provided at its free end with a 10 narrow, transparent pocket for receiving an index slip or label on which the address is usually printed in a single horizontal line.

Another object of the invention is to provide such an attachment for addressing machines which is simple, compact and inexpensive in construction, and whose parts are so organized and arranged that the same is readily adjustable for adapting it to different kinds of work.

25 A further object is the provision of an efficient and reliable attachment of this character which can be applied to and removed from present-day addressing machines without in any way altering their construction.

30 Other features of the invention reside in the construction and arrangement of parts which will be hereinafter fully described and particularly pointed out in the appended claims.

35 In the accompanying drawings:—

Figure 1 is a top plan view of the attachment embodying my invention and showing the same in position on the bed plate or table of an addressing machine. Figure 2 is an end view thereof. Figure 3 is an enlarged transverse section on line 3—3, Fig. 1. Figure 4 is an enlarged fragmentary longitudinal section on line 4—4, Fig. 1. Figure 5 is a top plan view of the attachment showing the parts in a different position and partly broken away for clearness. Figure 6 is a perspective view of the base or main supporting frame of the attachment. Figure 7 is a perspective view of the carriage thereof. Figure 8 is a similar view of the carriage slide. Figure 9 is a perspective view of a card printed by the attachment. Figure 10 is a top plan view of

a modification of the invention. Figures 55 11 and 12 are similar views showing the parts in different positions. Figure 13 is a perspective view of a card printed by this modified form of attachment. Figure 14 is a fragmentary section similar to Figure 3, showing the card-grippers automatically raised to release the card.

Similar characters of reference indicate corresponding parts throughout the several views.

While the attachment, forming the subject matter of this invention, is adapted for use in connection with any well-known addressing machines, that shown in Figs. 1, 2 and 3 of the drawings, by way of example, comprises a bed plate or supporting table 15 having a printing point or place 16 on its upper side for receiving the customary stenciled or embossed printing-plate 17 on which the address is grouped or arranged vertically in the usual manner shown in Fig. 1. Overlying the printing plate is the usual inked ribbon 18, and arranged for movement toward and from the latter to impress the printed matter on the card 19 or similar article is the roller platen 20. At its front end, the supporting table has a depending flange 21 provided with a plurality of longitudinally spaced threaded-openings 22.

In the preferred embodiment of the invention shown in Figs. 1 to 9 inclusive, the same comprises a base or supporting plate 23, of substantially angular form in plan, which is adapted to rest flatwise on the table 15 of the addressing machine and which is adjustably fastened thereto. For this purpose, the base-plate is provided at its front edge with a depending flange 24 containing a plurality of adjusting screws 23^a, 24^a, the screws 23^a engaging the threaded openings 22 in the table-flange 21 to effect the transverse adjustment of the base-plate in one direction, while the screws 24^a abut against the front face of said table-flange to effect the adjustment of the base-plate in the opposite direction. As shown in Figs. 1 and 6, the base-plate 23 is so shaped that it does not overlie the printing-plate 17.

Guided on the base-plate of the attachment for movement both transversely and longitudinally relative thereto and to the printing-plate 17 is a suitable carriage upon

which the card 19 or other article to be printed is supported. In its preferred construction, this carriage consists of a body-portion 25 arranged lengthwise of the base-plate 23, a transverse bar 26 extending rearwardly from one end of the body-portion, and a longitudinal bar 27 disposed substantially parallel with the latter and fastened at one end to the free end of said transverse bar, as shown in Figs. 1 and 7. Mounted on the underside of the carriage-body 25 is a slide or channel bar 28 which is guided for horizontal movement on a companion longitudinal channel bar 29 fixed to the top of the base-plate 23, as clearly shown in Fig. 6. The carriage is capable of a limited transverse movement relative to its channel bar 28 and for this purpose it is coupled with the latter by a pin and slot connection 30, 31, the slots 31 being preferably formed in the channel bar and disposed at an angle to the longitudinal center line thereof. A suitable handle or knob 32 is applied to the carriage-body to effect its convenient manipulation.

The numerals 33, 34 indicate two work-supporting plates arranged lengthwise of the carriage in spaced relation to provide a longitudinal slot or printing space 35 through which each printed line of the printing plate 17 is adapted to be independently exposed while the remaining lines thereof are concealed beneath one or both of the work supporting plates. The latter are detachably connected to the carriage-body 25 and to the longitudinal bar 27, respectively, and to this end these plates are provided at their outer longitudinal edges with ears or lugs 36 for receiving screws 37 or other appropriate fastenings. The plate 33 is provided at its outer longitudinal edge with an upright gage bar or flange 38 against which the corresponding edge of the card 19 is adapted to engage and at one end thereof with a transverse gage bar or lip 39 against which the adjoining end of the card is adapted to engage, thereby permitting the proper placing of the cards on the carriage preparatory to making an impression on them. As shown in Figs. 1 and 9, the relation of the parts is such that the various impressions are made in horizontal alignment near the top of the card, the particular card illustrated being used in an index wherein the marginal or top portions of the cards bearing the address or other matter are exposed.

The plate 34 is likewise provided with a longitudinal gage bar 40 and a transverse gage bar or lip 41 against which the corresponding edges of the card are adapted to abut, when it is desired to impress the address near the bottom edge of the card. In other words, when it is desired to print the address at the top of the card, the latter is placed on the plate 33 against its gages 38,

39, while when it is desired to make the impressions at the bottom of the card, the same is placed on the plate 34 against its gages 40, 41.

In order to prevent accidental displacement of the cards on their supporting plates 33, 34, each of the latter is provided with gripping devices which preferably consist of fingers 42 mounted on a horizontal rock shaft 43 journaled at its ends in suitable brackets 44 and having a spring 45 coiled thereon tending constantly to rock the shaft in a direction to bring the fingers into contact with the cards. At one end each rock shaft has a crank-handle 46 for rocking it in the opposite direction to release the fingers 42 from gripping engagement with the cards.

Means are provided for automatically governing or controlling the combined longitudinal and transverse movement of the carriage to effect the transposition of the vertical arrangement of the address on the printing plate 17 to the horizontal disposition thereof on the card 19. This movement

of the carriage is in a direction from right to left and is a step by step one, by which the printing space or slot 35 is brought successively into register with each line of the printing plate with the result that the "name", "street" and "city" are distributed in spaced relation and in horizontal alignment on the card. For this purpose, the ends of the guide-channel 29 are provided with stops preferably in the form of longitudinally-arranged adjusting screws 47, 48 fitted in blocks 49 and against which depending flanges 50 formed at opposite ends of the channel bar 28 of the carriage-body 25 are adapted to abut for limiting the extreme longitudinal movements of the carriage in opposite directions. Mounted on the base-plate 23 of the attachment in front of the carriage is a longitudinal rail 51 having blocks 52, 53 adjustable lengthwise thereof and normally held in a set position by screws 54.

The block 52 contains a stop in the form of a transverse adjusting screw 55 with which the front edge of the carriage-body 25 is adapted to engage for limiting the transverse, forward movement of the same. In its normal or initial position, the carriage assumes the position shown in Fig. 1, in which the right-hand end of the channel bar 28 is in engagement with the screw 47 and the front end of the carriage-body is abutting against the screw 55. In this position, the printing space 35 between the work-supporting plates 33, 34 is in register with the last line of the address on the printing plate 17, so that when the card to be printed is placed on said plates, such last line will be impressed thereon near the left hand end of the card when the roller platen 20 is operated.

The rail-block 53 has a stop preferably in

the form of a transverse adjusting screw 56 with which a stop-shoulder 57 on the carriage-body 25 is adapted to engage for arresting the same in moving it lengthwise 5 from the position shown in Fig. 1 to that shown in Fig. 5. The transverse movement of the carriage to bring the printing space 35 opposite the next line on the printing plate is effected simultaneously with the 10 longitudinal movement thereof by a beveled or cam face 58 formed on the carriage-body in advance of the top-shoulder 57, and into whose path the end of the screw 56 projects. When this beveled face encounters said 15 screw, the carriage-body is shifted transversely and rearwardly on its channel bar 28, the pins 30 and diagonal slots 31 permitting such movement. In this position, the card receives the impression of the second 20 line of the printing-plate at the right of and in horizontal alinement with the first impression.

The final movement of the carriage to the dotted line position shown in Fig. 5 is limited in a longitudinal direction by the 25 left hand stop-flange 50 of the channel bar 28 encountering the adjusting screw 48, while its transverse movement is limited by the carriage body pins 30 engaging the rear ends 30 of the companion slots 31 in said channel bar. In this position, the printing space 35 registers with the top line of the printing plate, with the card 19 in the proper position to receive its impression near the right 35 hand end thereof and in horizontal alinement with the first and second impressions.

If desired, means may be provided for automatically releasing the gripping fingers 42 from the card 19 after the same has been 40 printed. For example, as shown at the top of Fig. 1, and in Figs. 2, 3 and 6, such means may be in the form of a longitudinally adjustable trip device consisting of a standard 59 mounted on the rear end of the base-plate 23 and fastened thereto by a bolt 60 passing through a longitudinal slot 61 in the base of said standard. At its upper end, the latter has a beveled overhanging flange or deflector 62, facing toward the left, 50 with which the crank handle 46 of the rear rock shaft 43 is arranged to engage when the carriage is shifted from its extreme left-hand to its extreme right-hand position. Upon encountering this deflector, the crank handle is swung downwardly to rock the shaft 43 in the proper direction to raise its gripping fingers clear of the card, as shown 55 in Fig. 14. While in this position, the card may be readily removed and a new one 60 substituted for it, after which the carriage is moved to the initial position shown in Fig. 1.

Briefly stated, the operation of the apparatus is as follows:

65 The carriage 25 is moved to the initial

position shown in Fig. 1 bringing its printing slot 35 in register with the last line of the printing-plate 17, the remaining lines being covered by the plate 34 of the carriage. The card to be printed is then placed on the 70 supporting plates 33, 34 and against the gages 38, 39, and the roller platen 20 is operated to impress said last line on the card. The knob 32 is then grasped and the carriage shifted toward the left in a longitudinal 75 and rearward direction until the stop shoulder 57 encounters the stop screw 56. This brings the printing-slot 35 in register with the second line of the printing-plate, as shown in Fig. 5. Upon impressing this second 80 line on the card, it appears at the right of and horizontally in line with the first impression. The carriage is now again shifted to the left and rearwardly, being arrested in its longitudinal movement by the stop 85 flange 50 of the channel bar 28 striking the stop screw 48 and in its transverse movement by the carriage pins 30 striking the rear ends of the channel bar slots 31. This results in the printing-slot 35 registering 90 with the first or top line of the printing plate, so that the impression thereof on the card appears at its right-hand end and horizontally in line with the first and second impressions. The finished card is then removed and another substituted for it.

In the modification of the invention shown in Figs. 10 to 13 inclusive, the device is equipped to print two lines at a time instead of one and thereby serves as a check 100 as to whether or not the address is correct in all its details. This is especially desirable when the attachment is used on automatic addressing machines wherein the plates are delivered to and ejected from the printing place of the machine automatically at regular intervals. The various details of construction of this modified arrangement are identical with those of the structure previously described. In this case, however, 105 but one work-supporting plate 63 is employed which is removably fastened to the longitudinal bar 27 of the carriage and whose front longitudinal edge is recessed or cut away, as shown at 64. This recess extends from the left hand end of said plate for a distance not less than a longitudinal stop of the carriage 25, and the depth of the recess is about equal to the width of a line of the address. This arrangement is designed to print at the bottom of the card 110 65, which, in this instance, has a removable tab or projection 66 at its lower edge extending from end to end of the card.

In the use of this modified device, when 115 the carriage is in its initial position, as shown in Fig. 10, the last two lines of the address will first be impressed at the lower left-hand portion of the card, above its tab 66, after shifting the carriage a step, as 120 130

hereinbefore described; the next impression will be substantially centrally at the bottom of the card with the last line of the address appearing on the card-tab and the second-
 5 last line appearing on the card-body, as shown in Fig. 11; while after the second shift of the carriage, the final impression will be made on the lower right-hand portion of the card with the first line of the address appearing at the bottom of the card-
 10 body and the last two lines on the card-tab, as shown in Fig. 12. This results in the address on the printing-plate appearing in whole or in part in three distinct groups
 15 across the card with the "name," "street" and "city" disposed in horizontal alinement at the bottom of the card, as shown in Fig. 13. By this arrangement, the three groups may be compared to see if they all corre-
 20 spond. If they do, it will indicate that the several impressions were taken from the same printing-plate, while if they do not, it will indicate that another printing plate was automatically projected into operative pos-
 25 ition before the card in question was completed. After the comparison is made, the card-tab 66 is torn off, so that when the card is placed in an index of the character hereinbefore referred to, the complete ad-
 30 dress will appear in a horizontal line across the exposed bottom-portion of the card.

It will be noted that this improved attachment is readily adjustable to adapt it for use in connection with various types of address-
 35 ing machines now in use and that the stroke or step by step movement of the carriage is likewise adjustable to suit different kinds of work and to effect the printing on any de-
 sired part of the card.

40 I claim as my invention:—

1. The combination with a printing appa-
 ratus having a printing-plate bearing print-
 ed matter disposed in superposed lines, of a work-supporting carriage mounted on said
 45 apparatus and movable step by step both lengthwise and crosswise of said printing-plate, said carriage having a printing space arranged between its longitudinal edges to register successively with each of the lines of
 50 the printing-plate, while the remaining lines of the plate are covered by the carriage.

2. The combination with a printing appa-
 ratus having a printing plate bearing print-
 ed matter disposed in superposed lines, of a
 55 work-supporting carriage mounted on said apparatus for step by step movement longitudinally and transversely of said printing plate, said carriage including a pair of plates arranged in spaced relation to pro-
 60 vide a longitudinal printing space arranged to register successively and independently with each of the lines of the printing plate, and means for limiting the successive move-
 65 ments of said carriage.

66 3. The combination with a printing appa-

ratus having a printing-plate bearing print-
 ed matter disposed in superposed lines, of a work-supporting carriage mounted on said apparatus for movement longitudinally and transversely of said printing plate, means 70 for limiting the longitudinal movement of said carriage at predetermined points, and means for effecting transverse movement of said carriage substantially simultaneously with its longitudinal movement. 75

4. The combination with a printing appa-
 ratus having a printing-plate bearing super-
 posed lines of matter, of a work-supporting
 80 carriage movable longitudinally and trans-
 versely of said plate, stops arranged to arrest
 the carriage at different points in its longi-
 tudinal movement and additional stops ar-
 ranged to arrest the carriage at different
 85 points in its transverse movement.

5. The combination with a printing appa-
 ratus having a printing-plate, of a work-
 supporting carriage movable longitudinally
 and transversely of said printing-plate, a
 90 longitudinal guide member, a slide movable
 lengthwise on said guide member, and con-
 necting means between said carriage and
 said slide permitting transverse movement
 of the carriage relative to the slide.

6. The combination with a printing appa-
 ratus having a printing-plate, of a work-
 supporting carriage movable longitudinally
 and transversely of said printing plate, a
 95 longitudinal guide member, a slide movable
 lengthwise on said guide member and a pin
 and slot connection between said carriage
 and said slide, said slot being arranged
 100 obliquely to said guide member.

7. The combination of a printing appa-
 ratus having a printing-plate, of a work-
 supporting carriage movable longitudinally
 and transversely of said printing-plate, a
 105 longitudinal guide member having end-
 stops, and a slide connected to said car-
 riage and movable lengthwise on said
 guide member, said slide being arranged to
 110 engage said end-stops to limit the longitudi-
 nal movement of the carriage in both
 directions, the carriage being free to move
 transversely of said guide member.

8. The combination with a printing appa-
 ratus having a printing-plate, of a work-
 supporting carriage movable longitudinally
 and transversely of said printing-plate, a longitudinal guide member having
 115 end-stops, a slide connected to said carriage
 and movable lengthwise on said guide mem-
 ber, the carriage being free to move trans-
 versely of said guide member, said slide
 being arranged to engage said end-stops
 120 to limit the longitudinal movement of the
 carriage in both directions, and an interme-
 diate stop for said carriage interposed be-
 125 tween said end-stops.

9. The combination with a printing appa-
 ratus having a printing-plate, of a work-

supporting carriage movable longitudinally and transversely of said printing plate, a stop for limiting the longitudinal movement of the carriage, and means located in the path of longitudinal movement of the carriage for shifting it transversely of said printing plate.

10. The combination with a printing apparatus having a printing-plate, of a work-supporting carriage movable longitudinally and transversely of said printing-plate, a deflecting device arranged in the path of longitudinal movement of the carriage for shifting it transversely, and a stop arranged 15 to limit longitudinal movement of the carriage after its deflection.

11. The combination with a printing apparatus having a printing-plate, of a work-supporting carriage movable longitudinally and transversely of said printing plate, said carriage having a deflecting face and a stop-shoulder beyond said face and a stop arranged in the path of movement of said deflecting face and said stop-shoulder, for 25 first shifting the carriage transversely and then limiting its longitudinal movement.

12. The combination with a printing apparatus having a printing-plate, of a work-supporting carriage movable longitudinally and transversely of said printing-plate, a longitudinal guide member for said carriage, the latter being free to move transversely of said guide member, and stops for limiting the transverse movement of said carriage in both directions.

13. The combination with a printing apparatus, having a printing-plate, of a work-supporting carriage movable longitudinally and transversely of said printing-plate, a longitudinal guide member, a slide movable lengthwise on said guide member, a pin and slot connection between said carriage and said slide permitting transverse movement of the carriage relative thereto, one 40 end of the slot forming a stop for limiting such movement of the carriage in one direction, and a second stop arranged in the path of the carriage for limiting its transverse movement in the opposite direction.

50 14. The combination with a printing apparatus having a printing-plate, of a work-supporting carriage movable relatively to said printing-plate, a rock shaft mounted on said carriage and having gripping fingers arranged to normally engage the work, a crank-arm on said shaft, and a trip device arranged in the path of movement of said crank-arm for rocking said shaft to releasing position when the printing operation is completed.

55 15. An attachment for addressing machines, comprising a base-plate, and a work-supporting carriage mounted on said base-plate and movable both longitudinally and transversely thereof, said carriage having

a printing-space adapted to register with the lines of a printing plate.

16. An attachment for addressing machines, comprising a base-plate, a longitudinal guide member thereon, a slide movable 70 lengthwise on said guide member, a work-supporting carriage mounted on said slide to move therewith, and connecting means between said carriage and said slide permitting transverse movement of the carriage relative to the slide.

17. An attachment for addressing machines, comprising a base-plate, a longitudinal guide member thereon, a slide movable 80 lengthwise on said guide member, a work-supporting carriage mounted on said slide to move therewith, connecting means between said carriage and said slide permitting transverse movement of the carriage relative to the slide, and stops arranged at predetermined points on said base-plate and in the path of movement of the carriage for limiting its longitudinal and transverse movements.

18. An attachment for addressing machines, comprising a base-plate, a longitudinal guide member thereon, a slide movable lengthwise on said guide member, a work-supporting carriage mounted on said slide to move therewith, connecting means between said carriage and said slide permitting transverse movement of the carriage relative to the slide, stops arranged adjacent the ends of said guide member and in the path of movement of said slide, and an intermediate stop for the carriage interposed between said end-stops.

19. An attachment for addressing machines, comprising a base plate, a longitudinal guide member thereon, a slide movable lengthwise on said guide member, a work-supporting carriage mounted on said slide to move therewith, a pin and slot connection between said carriage and said slide for permitting transverse movement of the carriage relative to the slide, said connection determining the extreme transverse movements of the carriage in both directions, and means for arresting said carriage intermediate said extreme movements.

20. An attachment for addressing machines, comprising a base plate, a longitudinal guide member thereon, a slide movable lengthwise on said guide member, a work-supporting carriage mounted on said slide to move therewith, and a pin and slot connection between said carriage and said slide for permitting transverse movement of the carriage relative to the slide, the slot of said connection being arranged obliquely.

21. The herein-described method of reproducing the vertical series of lines of the printing plate of an addressing machine in a substantially horizontal line, which consists

in covering all but one of the lines of the plate, imprinting the uncovered line of the plate upon a receiving surface, uncovering the next line of the plate and covering its remaining lines, shifting the receiving surface lengthwise and crosswise of the plate in a step-like course to bring said uncovered

second line of the plate in horizontal alignment with the first line impressed on the receiving surface, and imprinting said uncovered second line of the plate on the receiving surface.

BENJAMIN G. RAND.
